INVENTOR.
Ralph Donath,
Attorney.

UNITED STATES PATENT OFFICE

2,330,684

BUMPER FOR COMMERCIAL VACUUM
CLEANERS

Joseph J. Colling, Pittsburgh, Pa.

Application October 18, 1941, Serial No. 415,573

1 Claim. (Cl. 15—1)

This invention relates to bumpers for portable commercial vacuum cleaners of the can type and has among its objects the provision of a resilient bumper.

Another object of the invention is to provide a bumper for commercial vacuum cleaners which may be used as a hand-hold by the operator for manipulating the cleaner or when emptying the dirt from the dirt can or dirt receptacle.

Still another object of the present invention is to provide a commercial vacuum cleaner, having a cylindrical dirt receptacle, with a resilient bumper which is mounted concentrically around the exterior and adjacent the top thereof.

Yet another object of the present invention is to provide a concentric elastic bumper around a cylindrical dirt can, mounted adjacent its top thereof, which may be used to great advantage to support the upper portion of the dirt can upon the floor while cleaning or removing the dust from the walls of the can.

A further object of the invention is to provide an efficient bumper for a portable commercial vacuum cleaner which may be efficiently used aboard a moving ship thereby preventing any damage to the room walls of the ship or to the body of the cleaner, especially during stormy weather, while the ship is rocking.

Another object of the invention is to provide a portable commercial vacuum cleaner with a resilient bumper that will be efficient in operation, simple in design and conveniently adapted for various purposes.

Yet another object of the invention is to provide a commercial vacuum sweeper with a resilient bumper which is inexpensive to manufacture, easily installed and one which will considerably add to the general appearance and efficiency of the apparatus.

Other objects of these improvements will appear in the course of the description of the device taken in connection with the accompanying drawing, wherein are shown two embodiments of the invention, but it is to be understood that changes, variations and modifications may be resorted to which come within the scope of the claim hereunto appended.

In the drawing wherein like numerals of reference designate corresponding parts throughout the several views,

Figure 1 is a perspective view of a portable commercial vacuum sweeper showing the improved bumper.

Figure 2 is a horizontal sectional detail view

of the dirt can or dirt receptacle on line 2—2 in Figure 1 showing the bumper installed.

Figure 3 is an enlarged detail view of the bumper on line 3—3 of Figure 2.

Figure 4 shows on a small scale, the posture of the vacuum cleaner, especially when used in rooms aboard ships or in rooms of buildings, in which the bumper serves to prevent injury to walls and furniture with which the cleaner may come in contact during the operation also to prevent damaging of the cleaning apparatus.

Figure 5 shows, on a small scale, the posture of the vacuum cleaner, with the motor fan assembly removed, when it is desired to clean out the dust receptacle; in this case, the bumper being used as a support for the upper portion of the dust can.

Figure 6 shows, on a small scale, the posture of the dust can portion of the vacuum cleaner in which the operator tilts the dust can by using the bumper as a hand-hold.

Figure 7 is a fragmentary perspective view of a modified construction of a bumper in which a detachable, tire-like resilient covering is being slipped over a tubular ring.

Referring now to the drawing it will be noted that the improvements of the present invention relates particularly to commercial vacuum cleaners of the cylindrical can type which are moved from room to room and attached to an electric wall socket by means of a flexible electric cord.

The numeral 10 designates as an entirety a commercial vacuum cleaner, such as extensively used for hotels, stores, schools, ships, etc., having a cylindrical dust can or dust receptacle 11 which is supported on casters 12. A removable top 13, held in position by clamps 14 of any suitable design, contain the electric motor and fan, better known in the trade as fan assembly (not shown), while the dust receptacle 11 is provided with a removable filter (not shown).

A flexible tube 15 is joined and firmly attached to the tubular projection 16 of the dust can 11 and carries at its free end a dust inhaling nozzle (not shown) of well known construction.

It is customary to supply electric energy to the vacuum cleaner 10 by means of a flexible cord or cable 17 which is attached at its free end to a plug 18.

The present invention is not concerned with the particular general and detail construction of a commercial vacuum cleaner above described, but the present invention is intended to feature the resilient bumper 19 as applied to commercial vacuum cleaners.

Referring now to Figures 1, 2 and 3, the bumper 19 comprises a circular rim 20 of convexo-concave cross-section, concentrically secured to the exterior surface 21 of the dust can 11 adjacent the top rim 22 thereof by means of three or more equally spaced distance pieces 23 of sufficient length so as to provide ample space between the 11 and the bumper 19 for the fingers of the user to readily grip the bumper 19 when used as a hand hold.

The said distance pieces 23 may be riveted to the dust can 11 and the ring 20 as shown, or, if desired the same may be welded or otherwise secured.

A preferably endless, elastic ring 24 of circular cross-section which is made of soft rubber or other resilient material is sprung into final position as best shown in Figure 3 of the drawing.

An alternative form of bumper is shown in detail in Figure 7. In this construction a tubular ring 25 is being used which is concentrically mounted around the exterior upper portion of the dust receptacle 11 and rigidly held in position by distance pieces 26 of similar design, or otherwise, as the ones described in the construction shown in Figure 3.

27 indicates a removable, resilient covering made of soft rubber or other similar material which snugly embraces the tubular ring 25, as shown in Figure 7. This resilient covering 27 may be molded of soft rubber and has the shape of a miniature automobile tire in cross-section and comprises a substantially thick center portion 28 and the gradually thinned out opposing free ends 29 and 30. By forming the covering 27 as shown, it is possible to readily attach to or remove from the latter from the ring 25 without tools.

When it is desired to remove the dust from the dust receptacle 11, the top 13 is readily removed by releasing the clamps 14, after which the filter (not shown) in the interior of the dust can is lifted out. The operator then grips the bumper 19, now serving as a hand-hold, with both hands and tilts the dust can 11 into a position as shown in Figure 6 for the purpose of emptying the dust.

In order to thoroughly remove the dust adhering to the interior walls of the dust can 11 the latter is tilted over so that the bumper 19 rests on the floor and the dust can assumes a position as shown in Figure 5.

In the heretofore described case the bumper 19 serves as a rest for the upper portion of the dust can 11.

After the filter (not shown) is again inserted into the dust can 11 and the top 13 is replaced into its normal position and locked by the clamps 14, the apparatus 10 is again ready for further operation.

Considered in its general aspect, the present invention may be defined as that improvement in commercial vacuum cleaners having a cylindrical body, which consists in providing an annular resilient bumper surrounding the upper portion of the dust receptacle which serves three distinctive purposes; firstly as a bumper while the apparatus is being moved about a room, especially on board of moving ships, thereby preserving the walls and the body and exposed parts of the apparatus, secondly as a hand-hold when it is desired to remove the dust from the dust can and thirdly as a support for the upper portion of the dust can when it is desired to remove the dust from the interior walls of the dust can.

At this time it may be mentioned that the outside diameter of the bumper should be of larger dimension than any exposed metal parts of the apparatus.

From the foregoing description taken in connection with the accompanying drawing, the construction of the bumper and the mode of attachment can be greatly modified and additions made without departing from the scope of the present invention and while describing two devices which are now considered to be the best embodiments thereof, it is to be understood that various changes of the minor details of construction or assembly may be resorted to without departing from the principle or sacrificing any of the advantages of the invention as defined in the appended claim.

I claim:

In a portable vacuum cleaner including a dust container normally disposed upright and having radially outstanding supports at its lower end projecting downwardly therefrom, and a removable cover for the upper end of the container carrying suction producing mechanism carried thereby, a combined bumper and handle for said container comprising a rim of appreciably greater internal diameter than said container, brackets extending radially of said rim between the inner periphery of the rim and the container with their inner ends secured to the container adjacent but in downwardly spaced relation to the upper end thereof and their outer ends fixed to the rim in spaced relation to each other circumferentially of the rim and midway the width of the inner face thereof to mount the rim in concentric spaced relation to the container, said rim having its inner face transversely arcuate to provide a smooth and unobstructed surface and a ring of elastic material carried by and fitting snugly about the rim and projecting outwardly from the rim a greater radial distance than the outstanding supports, the portion of the ring projecting from the rim having its exposed surface arcuate transversely to provide a smooth and unobstructed outer peripheral surface for the ring.

JOSEPH J. COLLING.
